INVENTOR'S

ATTORNEY,

UNITED STATES PATENT OFFICE

ELMER O. MILLER, OF BELOIT, KANSAS.

END GATE

Application filed February 17, 1930. Serial No. 429,016.

My invention relates to end gates for trucks, wagons and other vehicles used in hauling hogs, sheep, calves and other live stock, and one object is to provide an end gate of this character which will permit of rapid loading and unloading of the animals with little or no chance of their escaping while thus being loaded or unloaded.

A further object is to provide an end gate with a slidable section which may be opened from either side so that it may be used in connection with right or left hand chutes located at stockyards and other places where live stock is loaded or unloaded.

Another object is the provision of fastening means for holding the end gate securely in closed position, and yet which may be quickly released when it is desired to open said end gate.

With the above and other objects in view, which will hereinafter appear, reference will now be had to the accompanying drawing, in which:

Fig. 1 is a broken perspective view of a truck body equipped with my improved end gate.

Fig. 2 is a vertical section on line 2—2 of Fig. 3, of the end gate applied to the rear portion of the truck body.

Fig. 3 is a broken plan view of the end gate and the truck body.

Fig. 4 is an enlarged fragmentary section of one of a pair of fastening members for holding the slidable section of the end gate in closed position.

Referring in detail to the various parts of the invention, 2, in general, designates the rear portion of a truck body which may be of any usual or preferred construction. The end gate forming the present invention, consists of a main hinged section and a slidable auxiliary section, which latter is operably mounted in the former. The hinged section consists of outer and inner upright members 4 and 8, respectively, and a number of transverse members 6 firmly secured together. The outer upright members 4 are spaced from the inner members 8 and cooperate therewith and with the members 6 in providing a slideway for the auxiliary section, forming an impor-

tant part of the end gate, to operate. The upright members 4 and 8 are arranged at the ends and the middle portion, and the transverse members at the upper and lower portions of the main section to leave openings 55 for the passage of animals when the auxiliary section is slid to the right or left. The main section of the end gate is secured to hinge members 10 by elements 12, and said hinge members 10 are operably mounted upon a pintle 14 supported by hangers 16 secured to opposite sides of the truck body 2 by suitable fastening means 18.

The hinged section of the end gate is normally secured in closed position by cables 20 65 in the form of chains or ropes, attached at their rear ends to eye bolts 22 secured to one of the upper transverse members 6. The forward ends of the cables 20 are attached to the rearwardly extending heads 28 of pins 26 70 adapted to be inserted in eye bolts 32 and 36 secured to cleats 34 at the sides of the body 2. When securing the hinged section of the end gate in closed position the pins 26 are first partially inserted through the eye bolts 75 32 at an angle of about forty-five degrees. The forward ends of the pins 26 are then grasped and pulled backwardly to approximately a vertical position so that their lower portions may be inserted in the open eye bolts 36 which cooperate with the eye bolts 32 in holding said pins 26 in place.

When the forward ends of the pins 26 are pulled backwardly as stated they rock on the eye bolts 32 as levers on their fulcrums and draw the cables 20 taut so that the hinged section of the end gate will be firmly held in closed position. The tension of the cables 20 hold the pins 26 firmly in engagement with the eye bolts 32 and 36, so that said pins cannot 80 work upwardly out of place when subjected to the vibration of the vehicle while traveling on the road.

Referring now more particularly to the slidable section of the end gate forming an 85 important feature of the invention, it will be noted that it is mounted between the upright members 4 and 8 of the hinged section. Said slidable section consists of upright members 41 and transverse members 43 which are 90

firmly secured together by bolts or other suitable means. The bottom portion of the slide-
able section travels upon antifriction rollers
40 journaled on shafts 42 mounted in the lower
5 portions of the upright members 4 and 8. Resilient fastening members 44 are provided for securing the slideable section in closed position. Said fastening members are secured to the lower portions of the upright members
10 4 and have curved portions 46 adapted to spring into recesses 48 in the upright members 41 of the slideable section, as shown by Fig. 4 and thus lock said slideable member in open or closed position. The spring fastening members 44 are secured in place by screws
15 50 or other suitable means. Oppositely disposed handles 52 are secured to the ends of the slideable section so that the latter can be readily opened to the right or left.

20 When hogs, sheep and other small animals are to be loaded or unloaded the slideable section of the end gage is opened about half way as shown by Fig. 1. The foregoing operation provides a small opening through which the animals must pass one by one so that there will be no opportunity for the animals within the truck from getting out of control and escaping. When larger animals, as steers, are to be loaded or unloaded the end gate may be lowered on the hinges 10 to open
25 up the entire rear end of the body 2.

From the foregoing description it is apparent that I have provided an end gate having the advantages above pointed out, and while I have shown one form of the invention I reserve all rights to such other forms and modifications as properly fall within the spirit and scope of the invention as claimed.

Having thus described my invention, what
40 I claim and desire to secure by Letters Patent, is:

45 In combination with a vehicle body, a main end gate section operably connected to said body and consisting of inner and outer upright members forming the ends and middle portion of said section, and horizontal mem-
50 bers forming the upper and lower portions of said section and interposed between said upright members to provide an opening, an auxiliary section mounted to slide to the right or left in said opening; rollers in the lower portion of said opening and upon which said auxiliary section is adapted to operate; means for
55 securing the main section in closed position, and resilient means for securing the auxiliary section in closed position.

In testimony whereof I affix my signature.
ELMER O. MILLER.
